UNITED STATES PATENT OFFICE.

ERNEST LOUIS RANKIN, OF EAST SHEEN, ENGLAND.

BRAIDING-MACHINE.

1,179,558.

Specification of Letters Patent. Patented Apr. 18, 1916.

Application filed November 20, 1914. Serial No. 873,163.

To all whom it may concern:

Be it known that I, ERNEST LOUIS RANKIN, a subject of the King of Great Britain and Ireland, residing at 17 Portsm-
5 man avenue, East Sheen, Surrey, England, have invented certain new and useful Im-
provements in Braiding-Machines, of which the following is a specification.

This invention relates to braiding ma-
10 chines wherein upper and lower sets of bobbins are rotated in opposite directions by upper and lower spiders driven through bevel or other suitable gearing, and in which a number of slotted or gapped disks mount-
15 ed on the upper spider engage by a flange on their peripheries, grooves in the upper bobbin carriers which are mounted to slide on a circular track formed by the upturned edge of the lower spider, the threads from
20 the lower set of bobbins being passed under and over the threads of the upper set of bobbins by thread throwing arms which coöperate with the gaps or slots in the disks and with slots in the lower spider for that
25 purpose.

Now this invention has for its objects to simplify and improve the operation of the thread passing or throwing arms and incidentally the construction of the machine.

30 The invention is hereinafter described with reference to the accompanying drawings in which—

Figure 1 is a vertical section of part of a braiding machine constructed according to this invention, Fig. 2 is a part plan, Fig. 3 is a section taken along the line 3—3 Fig. 1. Fig. 4 is a similar view to Fig. 1 illustrating a modified form of construction.

Referring to Figs. 1 to 3 the upper and
40 lower spiders *a* *b* are driven in opposite directions by the bevel gear wheels *c* *d* which are geared to the bevel pinion *e* on the driving shaft *f*, the bevel wheel *c* being connected by a boss or sleeve *c*¹ thereon pro-
45 vided with clutch teeth, with similar teeth on the central boss or sleeve *b*¹ of the lower spider *b* and the bevel wheel *d* being keyed to the central shaft *g* which is keyed in the central boss or sleeve of the upper spider *a*.

50 The upper spider *a*, which as illustrated, consists of a circular plate or disk carries the gapped disks *h* which are formed with short spindles or cranks *h*¹ mounted to rotate in vertical bearings in the spider *a* near the outer edge thereof and carry pinions *i* which mesh with an internal ring of teeth *j*

formed in a cylindrical casting *b*² resting on the lower spider *b* and forming a removable extension thereof.

As shown, the bottom spider *b* is of hol-
60 low or box-like form, having an upwardly extending cylindrical outer wall on which bearings *b*³ are provided for a series of rock-
ing spindles *k* provided with ball cranks at their outer ends. At these ends the spindles
65 *k* are each fitted with a sliding pin *l* which has a ring or eye *m* encircling the ball of the rocking spindle *k*. The pin *l* is of square cross section and passes through a square hole in the head *n* of a pin mounted to os-
70 cillate in a bearing bracket *o* in the lower spider and carrying the thread throwing arm *p*. At the inner end of the ball crank rocking spindle *k* a head is provided having a square transverse aperture into which a pin *l*¹ of square cross section is arranged to slide, said pin having a ring or eye *m*¹ which fits over a ball spindle or arm *q* mounted radially on a central oscillating sleeve *r*.

75 The machine shown in Figs. 1 and 3 has eight radial arms or spindles *q* arranged in staggered relation to obtain the known two over two pattern of braiding and adapted to be connected with a corresponding number
80 of ball crank rockers *k*, but there can be as many ball spindles as is necessary, accord-
85 ing to the number of spools on the machine. The oscillating sleeve *r* revolves bodily with the bottom spider *b* and is oscillated by
90 means of a small crank or eccentric disk *s* supported in a journal bearing *t* carried around by the bottom spider.

95 The crank pin is engaged to the oscillating sleeve by means of a connecting rod *t*¹ and arm *t*². To the bottom end of the crank shaft *s*¹ is fitted a small pinion *s*² which revolves around a stationary gear *s*³ supported by the base plate *s*⁴ of the machine. In this way an oscillating movement is obtained
100 and the above mentioned radial arms or spindles *q* mounted on the oscillating sleeve *r* impart through the rocking spindles *k* the necessary motion to the thread throwing arms *p* to raise and lower the threads as re-
105 quired.

110 The method of lubricating the main bear-
ings of the flanged disks mounted on the top spider is as follows: A circular oil groove *u* is turned in the top spider, this groove hav-
ing radial ducts *u*¹ communicating with it which lead to the disk bearings. Centrifu-

gal action, when the machine is running causes the oil to flow through the ducts u to bearings in which the shanks h^1 of the disks h rotate.

- 5 In the modified form of construction shown in Fig. 4, the oscillating sleeve r carrying the ball spindles q is driven direct from the central shaft g through a spur wheel g^1 and pinion g^2 keyed on one end of 10 a vertical crank shaft g^3 which is mounted to revolve in a bearing b^4 in the spider b , and connected with the sleeve r by a connecting rod t^1 . This arrangement can be conveniently employed when a large number 15 of spindles q are used in the same machine requiring a sleeve of large diameter.

What I claim and desire to secure by Letters Patent is:—

- 20 1. In a braiding machine comprising upper and lower spiders driven in opposite directions and carrying upper and lower sets of bobbins or spools, a thread passing movement comprising a series of thread throwing arms, a sleeve mounted to revolve with the lower spider about the central vertical axis of the machine and carrying arms or spindles, means connected with the sleeve and rotated to impart to the revolving sleeve and its arms an additional oscillating motion about its axis of revolution, and means for transmitting the oscillating motion of the arms on the sleeve to the thread throwing arms.
- 25 2. In a braiding machine comprising upper and lower spiders driven in opposite directions and carrying upper and lower sets of bobbins or spools, a thread passing movement comprising a series of thread throwing arms, a sleeve mounted to revolve with the lower spider about the central vertical axis

of the machine and carrying arms or spindles, means connected with the sleeve and rotated to impart to the revolving sleeve and its arms an additional oscillating motion about its axis of revolution, and means for transmitting the oscillating motion of the arms on the sleeve to the thread throwing arms, the means for rotating the eccentric or crank to impart oscillating motion to the sleeve consisting of a gear wheel or pinion fixed to 50 the crank and gearing with a gear wheel secured coaxial with the central axis of the machine to a fixed part of the machine.

3. In a braiding machine comprising upper and lower spiders driven in opposite directions and carrying upper and lower sets of bobbins or spools, a thread passing movement comprising a series of thread throwing arms, a sleeve mounted to revolve with the lower spider about the central vertical axis 60 of the machine and carrying arms or spindles, means connected with the sleeve and rotated to impart to the revolving sleeve and its arms an additional oscillating motion about its axis of revolution, means for transmitting the oscillating motion of the arms on the sleeve to the thread throwing arms, ball crank rockers mounted in bearings in the lower spider, a sliding pin connecting one end of each rocker with the pivot of a 70 thread throwing arm, and a sliding pin and ball connection between the other end and one of said arms or spindles on the oscillating sleeve.

In testimony whereof I have affixed my 75 signature, in presence of two witnesses.

ERNEST LOUIS RANKIN.
